UNITED STATES PATENT OFFICE.

CHARLES WIRT, OF CHICAGO, ILLINOIS.

DESIGN FOR AN INSULATOR-BRACKET.

SPECIFICATION forming part of Design No. 21,379, dated March 8, 1892.

Application filed January 4, 1892. Serial No. 417,018. Term of patent 3½ years.

To all whom it may concern:

Be it known that I, CHARLES WIRT, a citizen of the United States, residing at Chicago, in the county of Cook and State of Illinois, 5 have invented and produced a new and original Design for Insulator-Brackets for Electric Wires, of which the following is a specification.

My invention relates to designs for insulator-brackets for electric wires. It is illustrated in the accompanying drawings, where- 10 in—

Figure 1 is a side view of one of my brackets. Fig. 2 is a plan view thereof.

Like parts are indicated by the same letters 15 in both figures.

A is the cylindrical part; C, a flat plate; D, a curved plate from the cylindrical portion to the flat plate, and E a part angularly disposed toward the part D and extending from the cylindrical portion of the flat plate. 20

I claim—

The design for an insulator-bracket, substantially as herein shown and described.

CHARLES WIRT.

In presence of—

FRANCIS W. PARKER,
VIRGINIA WILLEY.
